COVER LOCK AND EXTRACTOR CONTROL

Oscar W. Johnson, Rochester, N. Y., assignor to
The American Laundry Machinery Company,
Norwood, Ohio, a corporation of Ohio

Application July 12, 1941, Serial No. 402,136

13 Claims. (Cl. 210—72)

The invention relates to centrifugal extractors such as are used, for example, for removing moisture from articles of clothing or textile fabrics in laundries, dry cleaning establishments, and the like. Extractors of this nature are generally provided with power means for rotating a foraminous work container within an imperforate housing or curb, and with removable or hinged cover means for loading, unloading, and, in general, for access to the interior. Such extractors are further usually provided with means for starting and stopping the rotating work container at desired intervals, stopping being usually effected by the application of conventional braking means in conjunction with interruption of the power. The present invention is directed to the provision of means for insuring safe operation of extractors of this type, and is specifically directed to improved cover locking and clamping mechanisms, operatively associated with the aforementioned power means and braking means, whereby application of power to the work container is impossible, not only while the cover is in open position, but even, though closed, while securing means are detached, and further whereby opening of said cover is impossible so long as the work container continues to rotate, whether under power or inertia deceleration.

In conjunction with the improved cover locking means as aforesaid, I have provided improved brake application means, whereby brake application may be automatically controlled to take effect over a predetermined period so as to stop the rotatable container on expiration of a desired interval after initial brake application.

In the drawings attached herewith and forming a part of this specification,

Fig. 1 is a side elevation of the extractor showing generally the location of the lock and the automatic brake and control mechanism.

Fig. 2 is a front elevation of the cover lock mechanism, a portion of the outer casing thereof being broken away to expose the interior.

Fig. 3 is a side elevation of Fig. 2, the side of the casing thereof being broken away.

Fig. 4 is an enlarged fragmental sectional view taken on the line 4—4 of Fig. 2.

Fig. 5 is a fragmental view of the brake control mechanism in the extractor idle position, the cover being open and the brake released.

Fig. 6 is a view like Fig. 5 showing this mechanism in the extractor running position, the cover being closed and the brake released.

Fig. 7 is a plan view of a part of the extractor 55

looking in the direction of the arrows 7—7, Fig. 1, but showing the cover in the closed position.

Fig. 8 is a view of the brake mechanism looking in the direction of the arrows 8—8 of Fig. 1.

Fig. 9 is a detail sectional view taken on the line 9—9 of Fig. 8.

Fig. 10 is a diagram of the electrical circuits.

The extractor shown in the drawings is a conventional form comprising a curb 15, the base of which supports bearings, not shown, in which is journaled a spindle also not shown. To the upper end of the spindle is secured a basket 16, indicated in dotted lines, and to the lower end a combination brake drum and pulley 17. The pulley is connected by belts 18 to a motor pulley 19, the pulley being secured to the shaft of a motor 20 mounted on a bracket 21 fixed to the curb. This entire assembly is suspended by three rods 22 from three posts 23, respectively, which posts are fixed to a base 24.

The curb is provided from a cover 25 fixed to a shaft 26. This shaft is mounted in bearings in a bracket 27 supported by the curb to provide for movement of the cover to and from the closed position as shown in Fig. 7, and in Fig. 1 by the dash-dot lines. An arm 28 is provided on the cover. Connected to the end of this arm is a chain or cable 29 which is wrapped around a retriever pulley 30. The tension of the retriever is sufficient to counterbalance the weight of the cover to facilitate movement to and from the closed position.

The bearing bracket is provided with a pair of arms 31 provided with bumper springs 32 arranged to act as a cushion stop for the cover in movement to the full open position. The cover is also provided with an annular cushion ring 33, see Fig. 4. This is adapted to engage the curb, as shown, and to thereby provide a means of preventing noise and rattle during operation of the machine.

The cover is provided with a centering post 34. This post is conical in shape, and is adapted to register with a conical recess in a member 35 secured to the cover as shown in Fig. 4.

As will appear from the following description the cover is held in closed position by a lock member, and further by a cooperating clamping bolt. The lock member catches automatically by gravity, when the cover is moved to closed position, but is releasable only by energization of means under the control of a manually operable push button. To prevent operation of this mechanism while the work container is rotating, the push button is in series circuit with a cen-

trifugal mercury switch, mounted on the rotatable container, which makes contact only when at rest. Operation of the push button while the device is in operation accordingly has no effect on the cover lock, although, as will later appear, it does stop the rotation of the container by reason of other associated electrical circuits.

The cover is further secured by a manually operable securing device, with which is associated a switch member in series circuit with the electrical leads to the motor which drives the rotatable container. When this securing device is in the idle position, whether the cover is open or closed, the said switch is open and the motor cannot be started. When the cover is closed and the securing device is in the cover-securing position, the said switch is closed and the motor can be started. Under such conditions, as will appear, the cover lock cannot be released, this being possible only when the securing device is moved to an operative position. The motor circuits, therefore, are actively associated with the securing device, and not with the cover lock, as has heretofore been known. The construction and operation of the cover locking and securing devices, and their respective associated mechanical and electrical elements are now described.

The cover lock, generally designated 36, comprises a casing fixed to the side of the curb opposite the cover bearing bracket. In the casing, supported freely for rotative movement, is a shaft 37 to which is pinned a lock lever 38 supporting a lock pin 39. This pin is adapted to cooperate with a lock finger 40 secured to the cover arm 41. The shaft 37 also has fixed to it a lever 42. This lever is connected by a link 43 to a lever 44 which is pinned to the shaft 45. The shaft 45 also has pinned to it another lever 46 which is connected by a link 47 to the armature of a solenoid 48.

With the solenoid in deenergized condition, the weight of these parts, including the link 43 and the armature and the connected levers, is enough to bias the lock lever 38 in a clockwise direction, as seen in Fig. 4, and when the cover is in the closed position, as shown, to cause the lock pin 39 to normally engage in locking relation with the lock finger 40. When the solenoid is energized, the leverage system is rotated counterclockwise thereby removing the lock pin from locking relation with the finger 40.

The locking mechanism also includes a clamping means 49. This comprises a bolt 50 which is fixed to a shaft 51 supported by bearings in the casing. The upper end of this bolt is threaded as shown at 52 and is adapted to receive a wing nut 53. When the bolt is swung from the open position, as shown in Fig. 1, to the clamping position, as shown in Fig. 4, it engages in a slot 54 in the cover arm 41. Then when the wing nut is turned down, the shoulder thereof engages the top of the cover arm over the slot and securely clamps the cover in a closed position as governed by the centering post 34 and pilot member 35. In this position, the cushion ring 33 engages the curb 15.

The right end of the shaft 51, as viewed in Figs. 2 and 4, has a projecting pin 60 mounted eccentrically to the shaft center. When the clamping bolt is moved to the clamping position, this pin rotates and comes to a position shown in Fig. 4 just contacting a lateral branch arm 61 of the lever 38. This provides assurance that the lock pin 39, when once in locking engagement with the finger, will remain until the clamping bolt is removed and prevents any possibility of the

lock pin being forced out of locking engagement.

The shaft 51 has a cam 62 fixed to it. This cam is arranged to actuate a lever 63 pivotally mounted in a bracket at 64. The lower branch 65 of the lever is adapted to actuate a switch 66. When the clamping bolt is in open position, as shown in Fig. 3, the cam 62 is in actuating position, relative to the lever 63, which through its branch 65, has depressed the switch to open circuit position. When the bolt is moved to the clamping position, the cam is out of operating engagement with the lever and the switch is permitted to close.

The upper end of the clamping bolt is provided with a collar 67. This is provided to limit the opening movement of the wing nut. It is provided with a depending lug 68 which engages with a corresponding lug 69 on the wing nut which provides a stop but prevents a wedging action of the nut against the collar in the upper position.

I have provided, and will describe, braking means normally urged to applied position by a spring, but maintainable in released position by a latch. In order to permit brake application, the latch is tripped by a solenoid controlled by a timer device. The timer operation simultaneously opens a switch in the motor circuit thereby deenergizing the motor. The construction and operation of the brake mechanism and associated mechanical and electrical elements are now described.

The brake is the contracting band type. The band 75 is supported in alignment with the drum by three supporting blocks 76 spaced around the drum as indicated in Fig. 8. One end of the band 75 is fixed to a block 78 which in turn is secured to the bottom face of the curb as indicated in Fig. 1. To the block is secured an angle member 79. The block 78 and angle 79 constitute an anchorage. The depending branch 80 of angle 79 is slotted to receive a rod 81. One end of this rod is connected to a lever 82, see Figs. 8 and 9. The lever is freely mounted on a stud 83 secured to the curb. A lug 84 is provided on the hub of the lever 82 and this engages with a screw 85 threaded in a branch member 86 of a lever 87. The lever 87 is connected at its end to the other end of the brake band 75 by a pin 10. This lever 87 is provided with an arcuate slot 88 and through this slot extends a stud 89 which is threaded into a branch 71 of the lever 82. Normally this stud is turned up to tightly secure the levers 82 and 87 together for movement as an integral part. The screw 85 provides adjustment for the initial brake band setting and to compensate for wear of the band. When it is desired to make an adjustment of the band, the stud 89 is loosened and the screw 85 turned to produce the proper setting and the stud 89 is again tightened.

The other end of the rod 81 is pivotally connected to a bell crank 92 pivotally mounted in a bracket 93 as shown in Figs. 1 and 8. The other branch of the bell crank is pivotally connected to a rod 94 which extends upwardly into a housing 95 and is therein associated with control mechanism to be later described.

Interposed between the angle member 79 and a nut 96 on the rod 81 is a spring 97. With the brake in off position, this spring is in a compressed condition. When the rod 94 is released, as will later appear, the stored energy in this spring applies a braking force on the rod 81 in a direction to contract the brake band, and thereby apply the brake.

As before stated, the rod 94 extends upwardly into the housing 95. As shown in Fig. 5, this rod inside of the housing is provided with a collar 98 which has a finger 99 which engages in a notch in a latch 100 which is pivotally mounted at 101. This latch is held normally in the latching position by a blocking arm 102, as shown in Fig. 5. The arm is pivotally mounted at 103 and intermediate its pivotal and free ends it is connected to the armature of a solenoid 104. In the latched position of the rod 94 the brake has been released and the spring 97 has been compressed. When the solenoid 104 is energized, raising the blocking arm 102 to the dash-dot position of Fig. 6, the blocking effect on the latch is removed and the rod is free to move upwardly under the influence of the stored energy in the spring 97 so as to apply the brake. It will be noted that the pivotal point 101 of the latch is off center, relative to the notch, so that the holding effect is removed when the locking arm is removed. Means are also provided to raise the blocking arm 102 manually. This comprises a branch arm 105 provided with an adjustable screw 106 which is adapted to contact a push button 107 mounted in a side wall of the housing. Manually depressing this button produces the same effect on the arm as energization of the solenoid.

Numeral 110 designates generally an oil check. The piston 111 of this check is connected by an arm 112 with the rod 94. Its purpose is to produce a timed application of the brake and further to prevent shock due to a sudden application of the brake. The piston is provided with the usual controlling orifice 113 into which works a plunger 114. A screw 115 is provided for plunger adjustment. A ball check relief valve 116 permits unrestricted flow of oil in the return movement of the piston.

The operation of this mechanism is as follows:

When the latch 100 releases the rod 94, it moves upwardly at an unrestrained rate until the plunger 114 enters the orifice 113. It is then immediately snubbed and, at this point, the brake band engages the drum and begins brake application. From this point the further movement of the rod 94 by the spring 97 is under the control of the plunger valve. This mechanism may be set for a given braking time in the following manner.

With the screw 115 set at the upper limit, the adjusting nut 96 on the rod 81 is set so that when the brake is applied, the extractor basket, empty, will stop in 30 seconds. Now assume that it is desired, under operation, to stop the basket in 80 seconds. The adjusting screw 115 is screwed down positioning the plunger 114 relative to the orifice 113 so that the basket will stop in 80 seconds. It will be understood that the orifice 113 is just slightly larger in diameter than the plunger 114.

The upper end of the rod 94 is guided by a member 118. Above the rod 94 in the housing 95 there is another rod 120 guided for vertical movement by guides 121 and 122. This rod extends upwardly and is connected by a link 123 to a lever 124 fixed to a shaft 125 which is connected by universal coupling to the cover shaft 26. When the cover is in the closed position, this rod 120 is in the position of Fig. 6 and when the cover is opened, it is moved downwardly to the position of Fig. 5. Assuming that the brake has just been applied to stop the extractor,

the rod 94 will be in its uppermost position, not shown. When the cover is thereupon moved to the open position causing the rod 120 to be lowered, it engages the rod 94 in end to end relationship, returning it to its lower latched position and resetting the brake for the next operation.

Numeral 126 designates a normally closed limit switch. This switch is positioned so that it will be actuated to open by movement of one or the other two arms 127 and 128. 127 is pivoted at 129 and is provided with a roller 130 which is arranged to be engaged by the rod 94 when it is moved upwardly upon application of the brake. 15 In this case, the rod 94 engages the roller and rotates the arm 127 clockwise which depresses the stem of the switch. The actuation on the stem is through a spring 131. The arm 128 is pivoted at 132. When the cover is opened and the rod 120 is lowered, the arm 128 is rotated counterclockwise and through its engagement with arm 127 also depresses the stem of the switch 126 causing it to open. Thus, this switch 126 which is in the motor circuit, is normally closed when the brake is off and when the cover is closed. It is opened to break the motor circuit whenever the brake is applied or the cover is opened.

Numeral 133 designates a timer. This is motor driven and will be described in connection with the electrical circuits, diagram Fig. 10.

A centrifugal switch 134 is provided to cooperate with the cover lock, as will appear. This comprises a mercury tube mounted in an inclined position on the upper end of the motor shaft. When the motor is at rest, the mercury lies at the lower end and the switch is closed. When the motor is rotating, centrifugal force holds the mercury in the outer end of the tube 40 and the switch is open. A pair of collector rings 135 and suitable brushes 136 are provided for electrical connection to the terminals of the rotating switch.

The controlling apparatus comprises the switches 66, 126 and 134. The switch 66 is associated with the clamping bolt 50 in the cover lock housing 36. 126 is associated with the brake and cover control mechanism in the housing 95. 134 is a centrifugal switch associated with the motor as previously described. The control apparatus also comprises solenoids 48 and 104. 48 is associated with the cover lock in the housing 36, and 104 is associated with the brake apparatus as previously described. It also 55 includes the timer 133 and it further includes a start switch 137 and a stop switch 138.

The energization of the driving motor is controlled by a relay contactor switch 139. This switch includes an extra pair of contactors 152 60 associated with a maintaining circuit.

The functions of the above electrical apparatus and the various circuits will now be described in connection with a complete operation of the machine.

65 In starting, it will be assumed that the extractor is idle, and the cover is in the open position. Under these conditions the various parts of the mechanism will be in the position shown in Figs. 1 to 3, 5, 8 and 10. First of all the extractor is loaded with the goods to be centrifuged and the timer is set for the desired running period which connects terminals A₁ and A₂ and disconnects A₃ and A₄. The cover is then lowered to the closed position. The lock finger 40 engages the lock pin 39 in locking relationship. The clamp-

ing bolt is then rotated into the clamping position, as shown in Fig. 4, and the wing nut is turned down to securely hold the cover in place. Movement of the clamping bolt to this position causes the cam 62 to rotate out of engagement with the lever 63 and permits the switch 66 to close. The push rod 94, being already in the lower latched position as shown in Fig. 5, when the cover is closed the rod 120 is elevated to the position of Fig. 6, the arms 127 and 128 move to the left permitting the switch 126 to close. The start button 137 is now depressed connecting terminals E₁ and E₂. This establishes a circuit from L₁ through conductor 140, switch 66, conductor 141, switch 137, conductor 142, conductor 143, timer terminals A₁ to A₂, conductor 144, conductor 145, timer motor 146, conductors 147 and 148, switch 126, conductors 149 and 150 to L₃. This energizes the timer motor and sets the timer in operation. Simultaneously a circuit is also established from terminal A₂ by way of conductor 144, relay coil 151, conductors 147 and 148, switch 126, conductors 149 and 150 to L₃. This causes the contactor switch 139 to be closed energizing the drive motor 20 and also closing the maintaining contactor 152. As the motor begins to operate, the centrifugal switch 134 is opened, breaking circuit between terminals F₁ and F₂.

The closing of contactor 152 establishes the following maintaining circuit for the contactor switch 139. This is by way of conductor 140, switch 66, conductors 141 and 153, contactor 152, conductor 154, conductor 143, terminals A₁ to A₂ and thence through the timer motor and switch 126 to L₃, and simultaneously, through the coil 151 and switch 126 to L₃ as previously described. The maintaining circuit now being established, the start button 137 may be released.

When the time period for which the timer was set has elapsed, the timer returns to zero position and the contactor 155 of the timer switch returns to connect terminals A₃ and A₄, breaking connection between A₁ and A₂. This establishes the following circuit: from L₁ by way of conductor 140, switch 66, conductor 157, terminals A₃ to A₄, conductor 158, conductor 159, coil of solenoid 104, conductor 160, switch 126, conductors 149 to 150 to L₃. A circuit is also established through the signal lamp 161 by way of conductors 162, 163 and 150 to L₃. Illumination of the light designates the end of the extracting period.

Energization of the solenoid coil 104 causes the locking arm 102 to be elevated to the dash-dot position of Fig. 6. This releases the latch 100 which frees the rod 94 and the stored energy in the brake spring 97 becomes effective to apply the brake. This is performed under the control of the oil check 110 so that the braking effect is applied smoothly to cause the extractor basket to stop in a given time. Simultaneously, as the rod 94 moved upwardly and the brake was applied, the upper end of this rod engaged the roller 130 on the arm 127, causing it to rotate clockwise, opening the switch 126. This immediately opened the maintaining circuit for the solenoid coil 104. The upward movement of rod 94 is rather small, and finger 99 does not move above the upper end of latch 100. When solenoid 104 is deenergized arm 102 drops and engages shoulder 100a of latch 100. Subsequent opening of the cover depresses rod 94, latch 100 swings counterclockwise to locking po-

sition, and arm 102 drops to the position shown in Fig. 5.

When the basket has come to rest, the mercury in the centrifugal switch drops back to the inner end connecting the terminals F₁ and F₂. The cover 25 may now be opened but, first of all, the clamping bolt 50 must be released and moved out of engagement to the position shown in full lines, Fig. 1. This opens the switch 66 which, of course, prevents restarting of the motor. Now to unlock the cover so that it may be raised to the open position, the stop button 138 is depressed. This establishes a circuit from L₁ by way of conductor 140, conductor 165, terminals D₁ and D₂, conductor 166, solenoid coil 48, conductor 167, now closed switch 134, conductors 168 and 150 to L₃. The coil 48 is energized as long as the stop button is held depressed and the energization of this coil rotates levers 46 and 44, see Fig. 4, which elevates the link 43; and rotates lever 42 and lock lever 38, removing the lock pin from the lock finger 40 so as to permit opening of the cover. It will be understood that when the clamping bolt was moved out of clamping position, the pin 60 was moved away from engagement with the lever 42 so that the lock lever 38 was free to be moved.

The stop switch 138 serves two purposes, one of which has just been described, namely, to unlock the cover 25. The other purpose is to manually stop the extractor. In this case, during a running operation, when the stop button is depressed, a circuit is set up from L₁ by way of conductor 140, conductor 165, terminals D₁ to D₃, solenoid coil 104, switch 126, conductors 149 and 150 to L₃. During this operation, of course, the centrifugal switch 134 is open so that the circuit from terminal D₂ is not energized. Energization of coil 104 initiates the same operations as previously described for the time controlled stopping of the extractor. The stop button need only be held for an instant because immediately as the solenoid is energized and the latch 100 released, the switch 126 is opened and the stop button may be released. When the basket comes to rest and the centrifugal switch is closed, the stop button is again depressed to unlock the cover as before described.

Another way to terminate the operation is to depress the button 107 on the housing 95. This manually releases the latch 100 and permits application of the brake and opening of the motor circuit as previously explained in detail in connection with the operation of the timer and its effect on brake application.

When the cover is raised, the rod 120 is lowered to the position shown in Fig. 5. In its lowering movement it engages the upper end of rod 94, pushing it downwardly until it is latched by 100. This resets the brake to "off" position ready for the next running period. Through its engagement with the roller 130, the switch 126 is maintained open until the cover is again closed. The inclusion of the arm 128 makes it necessary to completely close the cover before it is possible to energize the motor circuits. Also the brake must be completely off and latched.

It is apparent from the above detailed description that I have provided mechanism whereby a cover for a curb member which houses a rotatable work container cannot be opened while said work container is rotating; it is further apparent that even after said container has come to rest, a further clamp removing operation is required to permit unlatching

of the cover so as to gain access to the container. The clamp removing operation effectively prevents further power rotation of the container whether the cover is open or closed.

I have further disclosed improved brake means, and apparatus for delayed control thereof, in operative association with other functions of the several elements of the apparatus described.

What I claim is:

1. A centrifugal extractor of the type described comprising a stationary curb, a basket rotatably mounted therein, electric motor means for rotating said basket, a cover for said basket mounted for opening and closing movement, a lock normally biased to hold said cover in closed position, means operatively associated with said lock and responsive to the rotation of said basket for effecting release of said lock only when said basket is at rest, securing means in addition to said lock for holding said cover in closed position, an electric circuit for energizing said motor, and switch means in said circuit and operatively associated with, and responsive to changes in position of said securing means whereby said motor-energization circuit is closed only when said securing means is in cover-securing position.

2. A centrifugal extractor of the type described comprising a stationary curb, a basket rotatably mounted therein, electric motor means for rotating said basket, a cover for said basket mounted for opening and closing movement, a lock normally biased to hold said cover in closed position, means operatively associated with said lock and responsive to the rotation of said basket for effecting release of said lock only when said basket is at rest, securing means in addition to said lock for holding said cover in closed position, an electric circuit for energizing said motor, switch means in said circuit and operatively associated with, and responsive to changes in position of said securing means whereby said motor-energization circuit is closed only when said securing means is in cover-securing position, and means carried by said securing means, and abutting said lock when said securing means is in cover-securing position, whereby release of said lock is then prevented.

3. A centrifugal extractor of the type described comprising a stationary curb, a basket rotatably mounted therein, a cover for said basket mounted for opening and closing movement, a lock for holding said cover in closed position, an electric circuit, lock releasing means in said circuit energizable by passage of current through said circuit whereby said lock is released when said circuit is closed, means responsive to the rotation of said basket for maintaining said circuit in open condition while said basket is in motion, electric motor means for rotating said basket, an electric circuit for energizing said motor, a switch for opening and closing said last named circuit, securing means in addition to said lock for maintaining said cover in closed position, and means associated with said securing means and with said switch for closing said switch only when said securing means is in cover securing position.

4. A centrifugal extractor of the type described comprising a stationary curb, a basket rotatably mounted therein, a cover for said basket mounted for opening and closing movement, a lock for holding said cover in closed position, an electric circuit, lock releasing means in said circuit energizable by passage of current through said circuit whereby said lock is released when said cir-

cuit is closed, means responsive to the rotation of said basket for maintaining said circuit in open condition while said basket is in motion, electric motor means for rotating said basket, an electric circuit for energizing said motor, a switch for opening and closing said last named circuit, securing means in addition to said lock for maintaining said cover in closed position, means associated with said securing means and with said switch for closing said switch only when said securing means is in cover securing position, and means associated with said securing means for preventing release of said lock while said securing means is in cover-securing position.

5. A centrifugal extractor of the type described comprising a stationary curb, a basket rotatably mounted therein, a cover for said basket mounted for opening and closing movement, a lock for holding said cover in closed position, an electric circuit, lock releasing means in said circuit energizable by passage of current through said circuit whereby said lock is released when said circuit is closed, centrifugal switch means in said circuit, and responsive to rotation of said basket, whereby said switch is opened during rotation of said basket, and closed when said basket is at rest, electric motor means for rotating said basket, an electric circuit for energizing said motor, a second switch for opening and closing said last named circuit, securing means in addition to said lock for maintaining said cover in closed position, and means associated with said second switch for closing said second switch only when said securing means is in cover-securing position.

6. A centrifugal extractor of the type described comprising a stationary curb, a basket rotatably mounted therein, a cover for said basket mounted for opening and closing movement, a lock for holding said cover in closed position, an electric circuit, lock releasing means in said circuit energizable by passage of current through said circuit whereby said lock is released when said circuit is closed, means responsive to rotation of said basket for closing said circuit only while said basket is at rest, a brake for said basket, means for applying said brake, a timer mechanism for energizing said brake applying means, electric motor means for rotating said basket, an electric circuit for energizing said motor, switch means for opening and closing said motor circuit, means operatively associated with said brake applying means for opening said switch when said brake applying means is energized, securing means in addition to said lock for maintaining said cover in closed position, a second switch in said motor circuit, and means associated with said securing means and with said second switch for closing said second switch when said securing means is in cover-securing position.

7. A centrifugal extractor of the type described comprising a stationary curb, a basket rotatably mounted therein, a cover for said basket mounted for opening and closing movement, a lock for holding said cover in closed position, an electric circuit, lock releasing means in said circuit energizable by passage of current through said circuit whereby said lock is released when said circuit is closed, means responsive to rotation of said basket for closing said circuit only while said basket is at rest, a brake for said basket, means for applying said brake, a timer mechanism for energizing said brake applying means, electric motor means for rotating said basket, an electric circuit

for energizing said motor, switch means for opening and closing said motor circuit, means operatively associated with said brake applying means for opening said switch when said brake applying means is energized, securing means in addition to said lock for maintaining said cover in closed position, a second switch in said motor circuit, means associated with said securing means and with said second switch for closing said second switch when said securing means is in cover-securing position, and means associated with said securing means for preventing release of said lock while said securing means is in cover-securing position.

8. A centrifugal extractor of the type described comprising a stationary curb, a basket rotatably mounted therein, a cover for said basket mounted for opening and closing movement, a lock for holding said cover in closed position, an electric circuit, lock releasing means in said circuit energizable by passage of current through said circuit whereby said lock is released when said circuit is closed, centrifugal switch means in said circuit and responsive to rotation of said basket whereby said centrifugal switch is opened during rotation of said basket and closed when said basket is at rest, a brake for said basket, means for applying said brake, a timer mechanism for energizing said brake applying means, electric motor means for rotating said basket, an electric circuit for energizing said motor, a second switch means for opening and closing said motor circuit, means operatively associated with said brake applying means for opening said second switch when said brake applying means is energized, securing means in addition to said lock for maintaining said cover in closed position, a third switch in said motor circuit, and means associated with said securing means and with said third switch for closing said third switch when said securing means is in cover-securing position.

9. A centrifugal extractor of the type described comprising a stationary curb, a basket rotatably mounted therein, a cover for said basket mounted for opening and closing movement, a lock for holding said cover in closed position, an electric circuit, lock releasing means in said circuit energizable by passage of current through said circuit whereby said lock is released when said circuit is closed, means responsive to the rotation of said basket for maintaining said circuit in open condition while said basket is in motion, electric motor means for rotating said basket, an electric circuit for energizing said motor, a switch for opening and closing said last named circuit, securing means in addition to said lock for maintaining said cover in closed position, means associated with said securing means and with said switch for closing said switch only when said securing means is in cover-securing position, a brake for said basket, means for applying and releasing said brake, means for normally biasing said brake to applied position, latch means associated with said brake applying means for preventing application of said brake, timer means for releasing said latch whereby brake application is initiated, and means for retarding application of full braking effect for a predetermined period after initiation of brake application.

10. A centrifugal extractor of the type described comprising a stationary curb, a basket rotatably mounted therein, a cover for said basket mounted for opening and closing movement, a lock for holding said cover in closed position, an electric circuit, lock releasing means in said circuit

circuit energizable by passage of current through said circuit whereby said lock is released when said circuit is closed, means responsive to the rotation of said basket for maintaining said circuit in open condition while said basket is in motion, electric motor means for rotating said basket, an electric circuit for energizing said motor, a switch for opening and closing said last named circuit, securing means in addition to said lock for maintaining said cover in closed position, means associated with said securing means and with said switch for closing said switch only when said securing means is in cover securing position, means associated with said securing means for preventing release of said lock while said securing means is in cover-securing position, a brake for said basket, means for applying and releasing said brake, means for normally biasing said brake to applied position, latch means associated with said brake applying means for preventing application of said brake, timer means for releasing said latch whereby brake application is initiated, and means for retarding application of full braking effect for a predetermined period after initiation of brake application.

11. A centrifugal extractor of the type described comprising a stationary curb, a basket rotatably mounted therein, a cover for said basket mounted for opening and closing movement, a brake for said basket, means for applying said brake, a timer mechanism for initiating operation of said brake applying means, electric motor means for rotating said basket, an electric circuit for energizing said motor, said electric circuit including three switches in series, said motor being energized only when all three said switches are closed, means operatively associated with said timer and with the first said switch whereby said switch is opened after the expiration of the period for which the timer is set, means operatively associated with said brake applying means and with the second said switch whereby said second switch is opened when said brake applying means is energized by said timer as aforesaid, securing means for maintaining said cover in closed position, and means operatively associated with said securing means and with said third switch whereby said third switch is opened only when said securing means is detached from cover-securing position.

12. A centrifugal extractor of the type described comprising a stationary curb, a basket rotatably mounted therein, a cover for said basket mounted for opening and closing movement, a brake for said basket, means for applying said brake, a timer mechanism for initiating operation of said brake applying means, electric motor means for rotating said basket, an electric circuit for energizing said motor, said electric circuit including three switches in series, said motor being energized only when all three said switches are closed, means operatively associated with said timer and with the first said switch whereby said switch is opened after the expiration of the period for which the timer is set, means operatively associated with said brake applying means and with the second said switch whereby said second switch is opened when said brake applying means is energized by said timer as aforesaid, securing means for maintaining said cover in closed position, means operatively associated with said securing means and with said third switch whereby said third switch is opened only when said securing means is detached from cover-securing position, a lock normally biased to hold

said cover in closed position, a second electric circuit, lock releasing means in said second circuit energizable by passage of current through said second circuit whereby said lock is released when said second circuit is closed, and means responsive to rotation of said basket for closing said second circuit only while said basket is at rest.

13. A centrifugal extractor of the type described comprising a stationary curb, a basket rotatably mounted therein, a cover for said basket mounted for opening and closing movement, a brake for said basket, means for applying said brake, a timer mechanism for initiating operation of said brake applying means, electric motor means for rotating said basket, an electric circuit for energizing said motor, said electric circuit including three switches in series, said motor being energized only when all three said switches are closed, means operatively associated with said timer and with the first said switch whereby said switch is opened after the expiration of the period

5 for which the timer is set, means operatively associated with said brake applying means and with the second said switch whereby said second switch is opened when said brake applying means is energized by said timer as aforesaid, securing means for maintaining said cover in closed position, means operatively associated with said securing means and with said third switch whereby said third switch is opened only when said securing means is detached from cover-securing position, a lock normally biased to hold said cover in closed position, a second electric circuit, lock releasing means in said second circuit energizable by passage of current through said second circuit whereby said lock is released when said second circuit is closed, a centrifugal switch in said second circuit and responsive to rotation of said basket whereby said centrifugal switch is opened during rotation of said basket and closed when said basket is at rest.
